UNITED STATES PATENT OFFICE.

FREDRICK M. NELSON, OF LOS ANGELES, CALIFORNIA.

DOOR LOCK.

Application filed December 10, 1923. Serial No. 679,626.

The present invention relates to door locks, and is somewhat similar to my invention shown and described in my copending application for U. S. Letters Patent, filed 5 November 27, 1922, Serial No. 603,650, entitled Door lock.

Both this and the invention of the aforementioned application are directed to combining with the door lock, of standard type, 10 means selectively operable by the door knob, to co-operatively engage a complementary pivoted arm, mounted on the door casing, to limit the opening of the door. While the invention of the said application is directed 15 to the broad idea of this means, selectively operable by the door knob or knobs, which throw the main bolt, and in its more specific aspects contemplates the use of an auxiliary or secondary bolt and connecting 20 mechanism attachable to locks now in use; the invention of the instant case contemplates the use of the main bolt both for locking the door and engaging the arm, so the whole may be combined in one lock. 25 In this, as well as in the previous case, I provide an arrangement whereby the mechanism which operates to limit the opening movement of the door may not be either operatively connected or disconnected except 30 when the door is closed. I also provide means to prevent throwing off the night latch—which prevents opening of the door by the outside knob—when the door is open so that when the door is once closed to dis- 35 connect the bolt from the arm it cannot be again opened from the outside without the use of a key.

The utility of my device is obvious, both 40 for securely holding the door ajar, such as to admit greater circulation of air to the room or permit communication with persons on the outside without danger of their forcing an entrance; it being particularly efficacious for the latter purpose as the bolt 45 is arranged to engage the arm immediately after the former is withdrawn from the locking plate.

A further feature of the invention is that 50 it is neat in appearance and practically all of the parts concealed from view, so there are no unsightly parts exposed to mar the finished appearance of the door or its casing. Also the arm is pivoted at its top and loosely mounted so that it will always drop 55 into place by gravity and not protrude or be in the way while not in use. Another fea-

ture is the arrangement of the several co-operating parts so they may be attached to the door and casing in such a manner that they may not be removed while interengaged 60 when the door is open.

The merits of my invention, together with a detailed description of its construction and operation, are fully set forth in the following specification. The present specific 65 embodiment of my invention is illustrated in the accompanying drawings to which reference is made in the specification.

In these drawings,

Fig. 1 is a fragmentary perspective view 70 of a typical door showing the application of my invention thereto in holding it ajar;

Fig. 2 is a full-sized view illustrating the interior mechanism of my lock and its co-operative locking plate secured to the door 75 casing, parts being shown in section for clarity of illustration;

Fig. 3 is a fragmentary view similar to that shown in Fig. 2, only showing the night latch push pins in locked position; 80

Fig. 4 is a full-sized view of the arm and its mounting means;

Fig. 5 is a perspective view of the arm mounting and complementary locking plate member;

Fig. 6 is a sectional plan view taken as indicated by the line 6—6 of Fig. 2; and

Fig. 7 is a fragmentary perspective view of the main bolt.

Referring now to the drawings and first 90 to Figure 1, the numeral 10 designates a typical door mounted by means of hinges 11 in its frame. In this view the door frame members are concealed from view by the trim 12, which is common in building construction.

The numeral 13 designates generally a typical mortise lock set into the swinging edge 14, of the door 10; this lock having an inner knob 15 for withdrawing the main bolt 16; the knob 15 having a 95 bearing in the cover plate 17 secured to the outer side rail of the door. The view shown in Fig. 1 is taken from the inner side of the door showing the latter swinging inwardly and being limited in its opening movement 100 by my improved device. This comprises a mechanism adapted to selectively actuate the main bolt 16 to co-operatively engage a slotted arm 18 pivotally mounted upon the side rail 19 of the door frame.

As I will more particularly hereinafter point out, the fundamental principles of my

invention embody the arrangement of a mechanism, in combination with the main bolt 16 of the lock, whereby the bolt may be selectively actuated by the door knob or knobs to engage or disengage the arm 18, which limits the opening movement of the door. My improvement also embodies means for preventing actuation of the main bolt by the outside knob, when the latter is operable independent of the inside knob, and when the bolt is interengaged with the arm 18. This will prevent throwing off the night latch dogs when the door is opened and then closing it and disengaging it from the arm; this arrangement operating to prevent again opening the door from the outside after it is once closed. This latter arrangement is adapted for use in connection with the locks of the type where the inner 20 and outer knobs are mounted on independent shafts and operable independent of each other to throw the main bolt; and where a latching means is provided to lock the door so that the bolt cannot be withdrawn 25 by rotation of the outside knob, yet may be withdrawn by rotation of the inside knob.

In this case I have shown the lock 13, exclusive of my improvement, to be one of the several well known types now on the market, in connection with which my improvement may be used. However, it is to be understood that I do not desire to limit myself to a lock of this particular type or one embodying this particular arrangement 35 of mechanism, as my improvement may be embodied in the construction of many well known locks now on the market, or one which may be designed for my particular purpose. Rather, the present showing is 40 merely for the purpose of clearly illustrating and describing the principle of my invention, and the manner in which it may be constructed and used, so that it may be clearly understood; and this intent is not 45 to be construed as a limitation of its broad and fundamental features.

The lock 13, referring first to Figs. 2 and 3, has a casing 20 formed of a back wall 21 having a flange 22 extending around its top, bottom and rear edges, all secured to a front securing plate 23, by means of which it is secured in a recess 24 extending inwardly from the edge 14 of the door 10, screws 25 being used for this purpose, as is common practice. A cover plate (not shown) is adapted to be secured to the casing 20, by suitable screws, to conceal the interior mechanism; the views of Figs. 2 and 3 being shown with this cover plate removed.

60 The main bolt 16 consisting of a head 26 and a shank 27 is slidably mounted in the casing 20; the head 26 sliding in a bearing aperture 28 in the front plate 23, while the shank 27 is slidably supported adjacent its inner end between spaced lugs 29 and 30

formed upon the side plate 21. An expansile helical spring 31 surrounding the shank 27 and confined between the head 26 and spaced lugs 29, normally holds the bolt 16 in its outermost position with the major portion of the head 26 extending beyond the outer face of the plate 23. The bolt 16 is normally held against outward movement by means of a cross bar 32 secured to its inner end abutting against spaced lugs 33 and 33^a formed upon an arm 34 of a lever plate 35. The arm 34 is normally held in engagement with the lugs 33 and 33^a, by the action of spring 31.

The plate 35 is substantially in the form of a bell crank having arms 34 and 36 and is pivoted at substantially the juncture of these arms upon a pin 37 carried by the side plate 21 of casing 20. An arm 38 is pivotally connected at its upper end to the plate 35, at a point rearwardly of its pivot 37, by means of a pivot pin 39; the arm 38 having an outwardly projecting shoulder 40 adjacent its lower or distal end. A bell crank lever 41 has a cylindrical hub portion 42, the opposite ends of which are revolvably journaled in bearing apertures (not shown) in both the front cover plate and rear cover plate 21 of the casing 20. A square shaft 43 extends through a similarly formed aperture 44 in the hub portion 42; and it is upon the outer end of this shaft, which extends through the cover plate, that the inner door knob 15 is rigidly secured. An arm 45, of the bell crank 41, has a face 46 adapted to engage the lug 33 upon arm 34; while its other arm 47 has a face 48 which engages the shoulder 40 upon the lower end of arm 38. The several previously described parts are held in their normal positions, as illustrated in Fig. 2, by the action of spring 31. This holds the bar 32 in engagement with lugs 33 and 33^a, arm 34 in engagement with lugs 30; the plate 35 holding arm 38 downwardly with the shoulder 40 in engagement with the face 48, of lever 47, which also holds face 46, of arm 45, in engagement with lug 33. A lug or boss 49 may be formed on the side plate 21 to extend outwardly in position to be engaged by the arm 47, of bell crank 41, to limit its throw in one direction, the reason for which I will later explain.

From the foregoing description it is obvious that the main bolt 16 may be withdrawn into the casing 20 by rotation of the inner knob 15, on the shaft 43, in either direction, that is, either to the right or left in Fig. 2. By rotating the knob and shaft 43 to the right, the bolt 16 will be withdrawn into the casing 20 by reason of the face 46 on arm 45 engaging lug 33 on arm 34, so the lugs 33 and 33^a will carry it rearwardly by engagement with the cross arm 32. Thence by rotating the knob and shaft 130

43 to the left in Fig. 2, the bolt will likewise be withdrawn into the casing by reason of the face 48 on arm 47 engaging under shoulder 40 and rotating the plate 35 upon its pivot 37, in the direction indicated by the arrow, through the medium of arm 38. This movement of the plate 35 carries the bolt rearwardly, as above described.

When the shaft 43 and bell crank 41 are 10 rotated to the left, rotating the plate 35 upon its pivot through the medium of the arm 38 and arm 47, the full movement may be had and the bolt withdrawn its full distance into the casing 20; but when the bell 15 crank is rotated to the right the arm 47 engages lug 49 which limits the rearward movement of the bolt 16 so that it is only withdrawn substantially half way into the casing 20. Thus rotation of the inner knob 20 15 to the right withdraws the bolt half way while its rotation to the left withdraws it to the full extent of its throw; that is, withdraws the head 26 entirely within its bearing 28 in the front plate 23.

25 The bolt 16 may be withdrawn by the outer knob (not shown) which is rigidly mounted upon a shaft 50; the latter having a bearing in an outside cover plate, similar to the inner cover plate 17, and also in an 30 inner block (not shown) which is fitted into a recess in the door. The shaft 50 carries a cam 51, which is normally in the position illustrated in Fig. 2. The shaft 51, on which the outer knob is mounted, has no 35 connection with the shaft 43 on which the inner knob is mounted, and rotates independently thereof. The periphery of the cam 51 normally engages the bottom face 52 of a cam block 53; the latter being vertically, slidably mounted between walls 54 and 55 formed on the bottom portion of the flange 24, which form a guideway. A small extension 56, on this bottom portion of the flange 24, a lug extension 57 engaging 40 the top edge of wall 54 and a lug extension 58 engaging the top edge of the wall 55, all form stops to limit the downward movement of the cam block 53, as well as the engagement of its bottom face 52 with the 45 periphery of the cam 51. An arm extension 59 extending upwardly between lugs 29 and 30 on the side plate 21, also serves to guide the cam block 53 and maintain it in rigid alinement when it has been moved upwardly 50 by the cam 51. The cam block 53 is recessed, as at 60, to extend around the hub 42 of the bell crank 41 when it is moved upwardly. The top face of lug 57 is adapted to engage the bottom face 61 of a 55 portion of the arm 38 which extends below the shoulder 48.

Thus, rotation of the outer knob and shaft 50, in either direction, causes cam 51 to raise the cam block 53, and withdraw the 60 bolt 16 through the medium of lug 57 en-

gaging the bottom face 61 of arm 38, and the latter rotating plate 35 about its pivot, in the direction indicated by the arrow in Fig. 2. With the outer knob, the bolt 16 may be drawn either half or full way back, 70 by rotating the knob in either direction, as there is no means in connection with this knob to limit its withdrawal, as in the case of the inner knob. However, this may be provided by forming a stop on the cam 51 75 which will limit its rotation in one direction.

The bolt 16 may also be withdrawn by means of a key, from the outside, when the door is locked, as will be hereinafter explained. The usual type of tumbler lock 80 85 62 is provided adjacent the top of the casing 20, which is adapted to be actuated by a key from the outside. This lock has an arm 63 which is adapted to be rotated by a key, in the direction indicated by the arrow (Fig. 2), when inserted from the outside. Arm 63 is adapted to engage the distal end of an arm 64 pivotally mounted upon a pin 65 carried by a secondary locking bolt 66. As the bolt 66 and mechanism which actuates it has no 90 connection whatsoever with my invention, I have not illustrated it in detail, but have only shown it in so far as in this type of lock it provides a mounting means for the arms 95 64. This, of course, may be varied and the arm 64 mounted directly upon the side plate 21. A lug or projection 67, on the inner side of arm 64, is adapted to engage an arm 68 of a bell crank 69; the latter pivotally mounted upon the side plate 21 by means of a pivot pin 70. The other arm 71, of the bell crank 69, is adapted to engage the arm 36 of plate 35; the engaging ends of these arms being properly formed to effect a sliding engagement.

By rotation of the arm 63 into engagement with the distal end of arm 64, the latter will be depressed or moved in the direction indicated by the arrow (Fig. 2), and this, through the medium of lug 67 engaging arm 68, will move the arm 71 downwardly, in the direction indicated by the arrow, which will also carry arm 36 of plate 35 downwardly as indicated by the arrow. This effects a rotation of the plate 35 which withdraws the bolt 16 within the front plate 23. By the use of the key actuating the lock 62, from the outside, the bolt 16 may be withdrawn either its full or an intermediate distance, as there is no stop means to limit this movement, as the arm 63 is adapted to be rotated only in one direction as shown. This withdrawal of the bolt 16 by a key from the outside actuates the mechanism to withdraw the bolt independently of the means actuated by either the inner or outer knobs. A lug 72, formed on the inner face of the side plate 21, forms a stop against which the arm 71 abuts so that it will always be in engagement with the arm 36 of plate 35. This, of course, is when 100 105 110 115 120 125 130

the plate 35 is in its normal position as illustrated in Fig. 2. The lug 67, on arm 64, will normally rest upon the arm 68 so that its distal end will always be in position to be engaged by the lock arm 63, except when the bolt 66 is extended to locking position. It may be here mentioned that the bolt 66 is designed to be thrown from the inside only by means of a mechanism actuated by a small knob 73, shown in Fig. 1.

In this type of lock the bolt 16 may always be withdrawn by rotation of the inner knob, while a means is provided for throwing a latch to prevent its withdrawal by rotating the outer knob. This is effected by a pair of push pins 74 and 75 operatively connected together by means of a rocker arm 76. Each of the pins 74 and 75 have reduced ends 77 mounted to slide in apertures 78 formed in the plate 23; these apertures being tapered larger towards their outer ends so the finger may be inserted to push the pins inwardly. The pins 74 and 75 are so mounted that when one is pressed inwardly its reduced end 77 will lie near the inner end of its aperture 78, while the opposite one will extend outwardly, as illustrated in Fig. 2. The rocker arm 76 is pivotally mounted at its center upon a pivot pin 79, carried by the side plate 21, and is pivotally connected at one end to the pin 75 by means of a pin 80 and at its opposite end to the pin 74, by means of a pin 81 carried by the latter and extended into an elongated slot 82. The pin 74 has an extension 83 on its inner end which slides between lugs 84, to support it in alignment; and this end 83 is adapted to extend over the lug 58 upon cam block 53 when the pin 74 is moved inwardly, as shown in Fig. 3. This prevents the cam block 53 being raised by the cam 51 on shaft 50, which prevents the bolt from being withdrawn by rotation of the outer knob. When it is desired to lock the door so that the bolt cannot be withdrawn by rotation of the outer knob, the pins 74 and 75 are moved from the position shown in Fig. 2 to that shown in Fig. 3. An inverted V-shaped lug 85, formed on the bottom of pin 74, engages a leaf spring 86 to yieldingly hold the push pins in either of their extreme positions.

A complementary locking plate 87 (see Fig. 5) is adapted to be mounted in a suitably formed recess in the side rail 19 adjacent the swinging edge 14 of the door 10. This may be secured in place by means of screws 88; and in order that it may not be removed when the door is ajar, by removing the screws 88, I provide an additional security in the form of a pin 89 adapted to extend through bores in the side rail 19 and through an aperture 90 in the plate 87. The head or inner end 91 of this pin, which is inserted from the inside, is covered by the trim 12 on its inner face, as shown in Fig. 6.

This plate has a complementary recess 92 into which the head 26 of bolt 16 is adapted to extend to lock the door; and a similar recess 93 into which the bolt 66 is adapted to be extended when in locked position.

The inner face of plate 87 is recessed, as at 94, to receive the arm 18; this arm having a pivot stud 95, preferably formed integral adjacent its upper end which is adapted to extend through a bearing bore 96 in the plate 87. The rear face of the plate 87 is recessed or enlarged as at 97, surrounding the bore 96, so the arm 18 may be securely held in place as by means of a washer 98 and cotter key 99. By this means the arm 18 cannot be removed from the plate 87 when the door is opened. The arm 18 has a longitudinal slot 100 into which the head 26 of bolt 16 is adapted to extend, as hereinafter explained. The recess 94 in the plate 87 forms a rear flange 101 against which one side of the arm 18 abuts when hanging in its normal vertical position, as illustrated in dotted lines in Fig. 4. The pivot stud 95 of arm 18, fits loosely within the bore 96 so that when otherwise disengaged it will drop by gravity into vertical position within the recess 94 and always be out of the way when not in use, to limit the opening of the door.

The bolt head 26 is clearly illustrated in Figs. 2, 6 and 7. It is formed with the usual bevel face 102 and has a reduced neck portion 103 adjacent its outer end, forming a T-head 104 thereon. The space surrounding the neck 103 between the T-head 104 and the main portion 26^a is of a width slightly greater than the thickness of the arm 18, so the latter may freely slide therein. An extension 105 is formed upon the plate 87 to extend outwardly in front of the recess 92, and this extension has a rounded or bevel face 106 adapted to be engaged by the bevel face 102 of the head 26 to force it inwardly against the action of spring 31 when the door is being closed. A bevel face 107 is also formed on the arm 18 in horizontal alignment with the face 106 to further force the bolt inwardly over the edge of this arm when the door is being closed and which, in effect, is a continuation of the face 106 when the arm 18 is normally hanging in its vertical position, as shown by dotted lines in Fig. 4.

When the door 10 is closed, and other parts of the lock are in their normal positions, the bolt head 26 will extend through the slot 100 and into the recess 92, as shown in Figs. 2 and 6. In this position the neck 103 is slightly beyond the arm 18. When it is desired to open the door, either the inner or outer knobs may be used, the outer knob being rotated in either direction while the inner knob will be rotated to the left in Figs. 1 and 2. This will withdraw the bolt 16 its full distance within the plate 23 and free of

the plate 87 and arm 18. When it is desired to connect the bolt head 26 with the arm 18, the inner knob is rotated to the right in Figs. 1 and 2, and when the arm 47 of bell crank 41 engages the knob lug 49, the head will be in position where the reduced neck portion 103 is in alinement with the arm 18, then by opening the door the spaced sides 18^a and 18^b will engage within the space surrounding the neck portion 103, as illustrated in Fig. 4, carrying the arm 18 with the bolt. The limit of inward movement of the door will be reached when the outer end of the arm 18 rises to the level of the bolt 16. In this position, and also from the time that it starts to swing the arm 18 about its pivot, the T-head 104 will extend across the slot 100 so the bolt cannot be withdrawn from its connection with the arm when the door is opened, even slightly. From this it is clear that the bolt may be only connected with or disconnected from the arm 18 when the door is closed; being connected by rotating the inner knob in one direction to withdraw it the proper distance to carry the arm 18 with it when the door is opened. To disconnect the bolt head 26 the arm 18 of the door is first closed and then the knob rotated in the proper direction to withdraw the bolt 16 its full distance, as above described. It may be here mentioned that the plate 87 is also recessed intermediate the recess 92 at its forward edge, as at 108, to allow passage of the T-head 104 when it is in interlocking engagement with the arm 18.

It is to be understood that the bolt 16 may be withdrawn by use of the outer knob, to effect engagement of the head 26 with the arm 18, if desired. This is done by rotating the outer knob sufficiently to withdraw the bolt head 26 the proper distance and into alinement for engagement with the arm 18. Also, this may be effected by use of the key in lock 62, through the medium of arm 64, bell crank 69 and plate 35, when it is desired to effect an interlocking of the bolt 16 with the arm 18 upon leaving a room.

In order that the push pins 74 and 75 may not be actuated when the door is opened to throw the pin 74 out of engagement with the lug 58 on cam block 53, so the bolt may be withdrawn from engagement with the arm 18 by use of the outside knob, when the door is closed, I provide the following mechanism:

An arm 109 is pivotally mounted upon a pin 110, carried by the side plate 21, and has an end 111 adapted to extend into a notch 111^a in the push pin 75 when the latter is in the position illustrated in Fig. 3; that is, when the end 83 of a push pin 74 is extended over the lug 58. The movement of the arm 109 is controlled by a lever arm 112, also pivotally mounted upon the pivot 110, with its distal end 113 adapted to engage the

rear face of bolt head 26. Arm 112 is normally held in engagement with head 26 by means of a leaf spring 114. A lug 115, on the arm 112, is adapted to engage the bottom side of the arm 109 and hold it upwardly when arm 112 is in the position illustrated in Fig. 2. A coil spring 116, surrounding the pin 110, engages both the arms 109 and 112 to yieldingly hold them towards each other; and when the arm 112 is in the position illustrated in Fig. 2 to hold the arm 109 down upon the lug 115. Thus, when the bolt 16 is withdrawn from plate 87 the arm 112 is carried rearwardly with it so that when the push pins 74 and 75 are in the position illustrated in Fig. 3, the end 111 will extend into notch 111^a, thereby holding these pins against movement whenever the bolt 16 is withdrawn. The connection between arms 109 and 112 is such that the slightest movement of the bolt 16 inwardly will effect a downward movement of arm 109 so that its end 111 will immediately engage in notch 111^a. That is in case the push pins 74 and 75 are in the positions illustrated in Fig. 3. But in case the push pins 74 and 75 are in the positions illustrated in Fig. 2, movement of the arm 112 rearwardly by the bolt 16 will merely let the end 111 rest upon the top edge of push pin 75; the spring 116 permitting full rearward movement of the arm 112, although the arm 109 is not carried with it.

From the foregoing it is clear that when it is desired to effect engagement of the bolt 16 with the arm 18, the door 10 is first closed and either the inner or outer knob, or the lock 62 properly actuated to withdraw the bolt the proper distance to be in alinement for engagement with the arm 18 after which the door may be opened and securely held against further opening. After this it is necessary to close the door fully before the bolt can be withdrawn from the arm. In case it is desired to prevent actuation of the lock when the door is open, so the door may not be closed and bolt 16 released from arm 18, the push pins 74 and 75 are moved to the positions illustrated in Fig. 3, which prevents withdrawal of the bolt by the outside knob. After this is done the door is closed and the bolt 16 withdrawn the proper distance either by the inner knob or through the medium of the lock 62 to effect its engagement with the arm 18 after which the door is opened. This withdrawal of the bolt 16, an intermediate distance, moves the arm 112 rearwardly which permits engagement of the end 111 of arm 109 in notch 111^a, as illustrated in Fig. 3. After this, the push pin 75 may not be pushed in when the door is opened.

It is clear that the bolt 16 may not be withdrawn at any time by the inside knob when the door is opened. When the push pin 74 is in the position illustrated in Fig. 3, a person leaving the room may effect an en-

gagement of the bolt 16 with arm 18 by use of a key in the lock 62, as hereinbefore described, without the necessity of using the outside knob which is locked against rotation.

Instead of using the stop lug 49 to be engaged by the arm 47, of bell crank 41, to limit the throw of the bolt 16 in one direction and thereby effect its engagement with the arm 18, this lug may be dispensed with and the bell crank 41 left free to be thrown in either direction to withdraw the bolt 16 its full distance, while a positive, manual actuated mechanism may be provided to limit the throw of the bolt 16 whether the knob 15 is rotated in either direction. This arrangement I have illustrated in Fig. 6; and while this device will be suitable to accomplish my purpose, it will be obvious that other arrangements may be devised without departing from the principle. This device consists of a pin 120 slidably mounted in a bore 121, in the door 10, in a similar bore 30 in the cover plate 122. It has a head 123, secured to its outer end, by means of which it may be pushed in inwardly; this head also serving as a stop to limit its inward movement. The pin 120 is normally held in outward position, as illustrated in dotted lines 35 in Fig. 6, by the action of a leaf spring 124, secured at one end to the cover plate 122, by means of a rivet 125; its opposite end being bifurcated to extend around the inner end of pin 120 and engaging a collar 126 fixed 40 thereon, spaced slightly from its inner end. The collar 126 also serves to engage the inner face of cover plate 122 to limit the outward movement of the pin. The pin may be so mounted that its head 123 will be adjacent the inner knob 15, so that it may be pushed inwardly by the thumb of the hand which is used to turn the door knob. This will necessitate the use of only one hand in effecting engagement of the bolt 16 with the 45 arm 18.

When the pin 120 is pushed inwardly it will engage the rear face of the bolt head 23 to limit its inward movement, as shown by dotted lines in Figs. 2 and 6, so the reduced 50 neck portion 103 will be in alinement with the arm 18 to engage and carry the latter with it when the door is opened. When the pin 120 is in its normal inoperative position, as held by the spring 126, the bolt 16 may 55 be withdrawn its full distance by rotating the inner knob in either direction. Thus a conscious, positive, manual operation is required when it is desired to operatively connect the bolt 16 with the arm 18, which 60 will obviate annoyance to persons not familiar with this type of lock, in case they should throw the knob to the right in Fig. 2, when the lug 49 is used and connect the bolt 16 with the arm 18 when not intending to do 65 so. This latter type of construction will be

preferred; however, either it or the lug 49 may be used.

While I have shown the preferred specific embodiment of my invention, I reserve the right to make such changes or modifications 70 in structure as will properly come within the scope of the appended claims. For instance, a special type of lock may be designed to carry out the principles of my invention without the use of the particular lock mechanism hereinbefore described; or it may be used or embodied in many of the well known types of locks now on the market. It may also be embodied in a lock in which the inner and outer knobs are both mounted upon 75 the same shaft to be actuated together. It is only the locking features of my arrangement, which prevent unauthorized disconnection of the bolt 16 from the arm 18 when the door is closed, that I contemplate embodying in locks of the type in which the inner and outer knobs operate independently of each other.

Having described my invention, I claim:

1. In combination, a door having a bolt, 90 a door knob operatively connected by means to actuate said bolt, a complementary locking plate adapted to be secured to the door casing and engageable by the bolt, a longitudinally slotted arm adapted to be pivotally 95 mounted on the door casing intermediate the lock and locking plate, the bolt extending through the slot in the arm to engage the plate and having a portion adapted to interlock with the arm, the operative connection 100 between the door knob and bolt including means to withdraw the bolt from the plate and arm to open the door when the knob is turned in one direction and to withdraw the bolt an intermediate distance to clear the 105 plate and effect an engagement with the arm to limit the opening of the door when the knob is turned in the opposite direction.

2. In combination, a door lock having a bolt, a door knob operatively connected to 110 actuate said bolt, a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, the arm and bolt being engageable and 115 disengageable only when the door is closed, the operative connection between the door knob and bolt including means to withdraw the bolt from the plate and arm to open the door when the knob is turned in one direction and to withdraw the bolt an intermediate 120 distance to clear the plate and effect an engagement with the arm to limit the opening of the door when the knob is turned in the opposite direction.

3. In combination, a door lock having a 130

- 5 bolt, inner and outer door knobs operatively connected to independently actuate said bolt, a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, 70 the arm and bolt being engageable and disengageable only when the door is closed, the said door knobs being operable to either withdraw the bolt from the plate and arm to open the door or to an intermediate distance to effect its engagement with the arm to limit the opening of the door, and latching means in connection with the outer knob to prevent its operation to withdraw the bolt when it is in engagement with the arm.
- 10 4. In combination, a door lock having a bolt, inner and outer door knobs operatively connected to independently actuate said bolt, a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, 75 the arm and bolt being engageable and disengageable only when the door is closed, the said door knobs being operable to either withdraw the bolt from the plate and arm to open the door or to an intermediate distance to effect its engagement with the arm to limit the opening of the door, and latching means in connection with the outer knob to prevent its operation to withdraw the bolt when it is in engagement with the arm.
- 15 5. In combination, a door lock having a bolt, inner and outer door knobs operatively connected to independently actuate said bolt, a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, 80 the arm and bolt being engageable and disengageable only when the door is closed, the said door knobs being operable to either withdraw the bolt from the plate and arm to open the door or to an intermediate distance to effect its engagement with the arm to limit the opening of the door, and latching means in connection with the outer knob to prevent its operation to withdraw the bolt when it is in engagement with the arm.
- 20 6. In combination, a door lock having a bolt, inner and outer door knobs operatively connected to independently actuate said bolt, a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, 85 the arm and bolt being engageable and disengageable only when the door is closed, the said door knobs being operable to either withdraw the bolt from the plate and arm to open the door or to an intermediate distance to effect its engagement with the arm to limit the opening of the door, and latching means in connection with the outer knob to prevent its operation to withdraw the bolt when it is in engagement with the arm.
- 25 7. In combination, a door lock having a bolt, means to actuate said bolt, a complementary locking plate adapted to be secured to the door casing and engageable by the bolt, a slotted arm adapted to be pivotally mounted on the door casing intermediate the lock and locking plate, the bolt extending through the slot in the arm to engage the plate and having a portion adapted to interlock with the arm, 90 and means selectively operable to limit the throw of the bolt to effect its engagement with the arm.
- 30 8. In combination, a door lock having a bolt, means to actuate said bolt, a complementary locking plate adapted to be secured to the door casing and engageable by the bolt, a slotted arm adapted to be pivotally mounted on the door casing intermediate the lock and locking plate, the bolt extending through the slot in the arm to engage the plate and having a portion adapted to interlock with the arm, 95 and manually operable means selectively operable to limit the throw of the bolt to effect its engagement with the arm.
- 35 9. In combination, a door lock having a bolt, a door knob operatively connected to actuate said bolt, a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, 100 the door knob being operable to withdraw the bolt from the plate the full distance to open the door or an intermediate distance to effect its engagement with the arm to limit the opening of the door, and means selectively operable to limit the throw of the bolt to effect its engagement with the arm.
- 40 10. In combination, a door lock having a bolt, inner and outer door knobs operatively connected to independently actuate said bolt, a complementary locking plate adapted to be secured to a door casing and engageable by the bolt, a longitudinally slotted arm adapt- 105

- ed to be pivotally mounted on the door casing intermediate the lock and locking plate, the bolt extending through the slot in the arm to engage the plate and having a portion adapted to interlock with the arm, the said door knobs being operable to either withdraw the bolt from the plate and arm to open the door or an intermediate distance to effect its engagement with the arm to limit the opening of the door, means selectively operable to limit the throw of the bolt to effect its engagement with the arm, and latching means in connection with the outer knob to prevent its operation to withdraw the bolt when it is in engagement with the arm.
11. In combination, a door lock having a bolt, inner and outer door knobs operatively connected to independently actuate said bolt; a complementary locking plate adapted to be secured to a door casing and engageable by the bolt, a longitudinally slotted arm adapted to be pivotally mounted on the door casing intermediate the lock and locking plate, the bolt extending through the slot in the arm to engage the plate and having a portion adapted to interlock with the arm, the arm and bolt being engageable and disengageable only when the door is closed, the said door knobs being operable to either withdraw the bolt from the plate and arm to open the door or an intermediate distance to effect its engagement with the arm to limit the opening of the door, means selectively operable to limit the throw of the bolt to effect its engagement with the arm, latching means to prevent operation of the outer knob to withdraw the bolt, and means to prevent throwing off said latching means when the bolt is in engagement with the arm.
12. In combination, a door lock having a bolt, means to actuate said bolt, a complementary locking plate adapted to be secured to the door casing and engageable by the bolt, a slotted arm adapted to be pivotally mounted on the door casing to depend intermediate the lock and locking plate, the bolt being normally freely extensible through the slot in the arm to engage the plate and having an intermediate portion adapted to interlock with the arm when the arm is swung from its normal depending position thereby, the bolt actuating means being adapted to withdraw the bolt an intermediate distance to engage said arm to limit the opening of the door, or its full distance to clear the arm to entirely open the door.
13. In combination, a door lock having a bolt, means to actuate said bolt, a complementary locking plate adapted to be secured to the door casing and engageable by the bolt, a slotted arm adapted to be pivotally mounted on the door casing to depend intermediate the lock and locking plate, the bolt being normally freely extensible through the slot in the arm to engage the plate and having an intermediate portion adapted to interlock with the arm when the arm is swung from its normal depending position thereby, the bolt being normally freely extensible through the slot in the arm to engage the plate and having an intermediate portion adapted to interlock with the arm when the arm is swung from its normal depending position thereby, the arm and bolt being engageable and disengageable only when the arm is in its normal depending position, the door knob being operable to withdraw the bolt from the plate the full distance to open the door or an intermediate distance to effect its engagement with the arm to limit the opening of the door.
14. In combination, a door lock having a bolt, a door knob operatively connected to actuate said bolt, a complementary locking plate adapted to be secured to the door casing and engageable by the bolt, a longitudinally slotted arm adapted to be pivotally mounted on the door casing to depend intermediate the lock and locking plate, the bolt being normally freely extensible through the slot in the arm to engage the plate and having an intermediate portion adapted to interlock with the arm when the arm is swung from its normal depending position thereby, the arm and bolt being engageable and disengageable only when the arm is in its normal depending position, the bolt actuating means being adapted to withdraw the bolt an intermediate distance to engage said arm to limit the opening of the door, or its full distance to clear the arm to entirely open the door.
15. In combination, a door lock having a bolt, a door knob operatively connected to actuate said bolt, a complementary locking plate adapted to be secured to a door casing and engageable by the bolt, a longitudinally slotted arm adapted to be pivotally mounted on the door casing to depend intermediate the lock and locking plate, the bolt being normally freely extensible through the slot in the arm to engage the plate and having an intermediate portion adapted to interlock with the arm when the arm is swung from its normal depending position thereby, the arm and bolt being engageable and disengageable only when the arm is in its normal depending position, the door knob being operable to withdraw the bolt from the plate the full distance to open the door or an intermediate distance to effect its engagement with the arm to limit the opening of the door.
16. In combination, a door lock having a bolt normally held yieldingly extended, means to withdraw said bolt against the action of its yielding means, a complementary locking plate adapted to be secured to a door casing and engageable by the bolt when normally extended, a longitudinally slotted arm adapted to be pivotally mounted at its upper end on the door casing to depend intermediate the lock and locking plate, the bolt being normally freely extensible through the slot in the arm to engage the plate and having an intermediate portion adapted to interlock with the arm when the arm is swung from its normal depending position thereby, the arm and bolt being engageable and disengageable only when the arm is in its normal depending position, the bolt actuating means being adapted to withdraw the bolt an intermediate distance to engage said arm to limit the opening of the door, or its full distance to clear the arm to entirely open the door.

slot in the arm to engage the plate and having an intermediate portion adapted to interlock with the arm when the arm is swung from its normal position thereby, the bolt 5 actuating means being adapted to withdraw the bolt an intermediate distance to engage said arm to limit the opening of the

door or its full distance to clear the arm and entirely open the door.

In witness that I claim the foregoing I 10 have hereunto subscribed my name this 26th day of September, 1923.

FREDRICK M. NELSON.
